SOCKET WRENCH

John Deliso, Shrewsbury, Mass.

Application February 19, 1954, Serial No. 29,116

Term of patent 14 years

(Cl. D54—16)

FIG. 1

FIG. 2

FIG. 3

To all whom it may concern:

Be it known that John Deliso, a citizen of the United States, residing at Shrewsbury, in the county of Worcester and State of Massachusetts, has invented a new, original, and ornamental Design for a Socket Wrench, of which the following is a specification, reference being had to the accompanying drawing, forming part thereof.

Fig. 1 is a side elevational view of a socket wrench showing my new design;

Fig. 2 is an elevational view looking at the top of Fig. 1; and

Fig. 3 is an elevational view to a larger scale looking at the left of Fig. 1, the handle portion being omitted for convenience of illustration.

I claim:

The ornamental design for a socket wrench, as shown.
